CLAIM

The ornamental design for an adhesive tape dispenser, as shown and described.

DESCRIPTION

FIG. 1 is a right side perspective view of an adhesive tape dispenser according to our design with a gate in a first position;

FIG. 2 is a right side plan view thereof;

FIG. 3 is a left side plan view thereof;

FIG. 4 is a rear elevational view thereof;

FIG. 5 is a front elevational view thereof;

FIG. 6 is a top plan view thereof; and,

FIG. 7 is a right side perspective view thereof with the gate in a second position.

The broken lines show an adhesive film/ tape roll and an adaptor for same. Accordingly, the broken lines showing environment in the drawings are for information purposes only and form no part of the claimed design.
